DESIGN FOR A TELESCOPE SIGHT

Chester W. Hageman, Middletown, Conn., assignor to The Lyman Gun Sight Corporation, Middlefield, Conn., a corporation of Connecticut

Application June 24, 1935, Serial No. 57,387

Term of patent 14 years

To all whom it may concern:

Be it known that I, Chester W. Hageman, a citizen of the United States, residing in Middletown, in the county of Middlesex and State of Connecticut, have invented a new, original, and ornamental Design for Telescope Sights, of which the following is a specification, when taken in connection with the accompanying drawing, in which

Fig. 1 is a plan view of a telescope sight embodying my invention;

Fig. 2 is an end view of the same, taken from the right-hand end as viewed in Fig. 1;

Fig. 3 is a view similar to Fig. 1 but showing on an enlarged scale the left-hand end of the telescope sight, the remainder of the sight being broken away for convenience of illustration, and

Fig. 4 is a view similar to Fig. 3 but showing the right-hand end of the telescope sight.

I claim:

The ornamental design for a telescope sight substantially as shown and described.

CHESTER W. HAGEMAN.
